UNITED STATES PATENT OFFICE.

DAVID SYM BAIN, OF NORDEGG, ALBERTA, CANADA.

GATE-ACTUATING MECHANISM.

Application filed June 18, 1921. Serial No. 478,577.

To all whom it may concern:

Be it known that I, DAVID S. BAIN, a subject of the King of Great Britain, residing at Nordegg, in the Province of Alberta, 5 Canada, have invented certain new and useful Improvements in Gate-Actuating Mechanisms; and I do hereby declare that the following is a full, clear, and exact description of the invention, such as will enable others 10 skilled in the art to which it appertains to make and use the same.

The present invention relates to new and useful improvements in a gate actuating mechanism used particularly in mines for 15 opening and closing the gate in front of and in advance of the mine cars.

The primary object of the invention is the provision of a mechanism whereby a gate 20 will be opened or closed upon the passage of a mine car through the mine shaft.

Another object of the invention is the provision of a gate actuating mechanism, including pivoted presser rails for engaging with the car wheels of a mine car when passing 25 through the shaft along the track whereby upon the depression of said members, the gates will be swung to open position and after the car passes, the gates will be automatically closed, by means of suitable 30 weights connected with the said mechanism.

Still another object of the invention is the provision of novel means for mounting the gates within the mine shaft and automatically moving them to open and closed 35 positions upon the passage of a car therethrough.

A still further object of the invention is the provision of an apparatus such as above referred to which will be comparatively 40 simple and inexpensive to manufacture, reliable and efficient in use and readily operated.

With the above and other objects in view, the present invention resides in the novel 45 features of construction, formation, combination and arrangement of parts to be hereinafter more fully described, claimed and illustrated in the accompanying drawing, forming a part of the present application; and in which,

Figure 1 is a vertical longitudinal sectional view taken through a portion of a mine shaft showing the invention positioned therein;

Figure 2 is a horizontal sectional view 55 thereof;

Figure 3 is a transverse sectional view, taken through the lower portion of the structure, showing the rails in cross section and the presser bar in side elevation; 60

Figure 4 is an enlarged view showing a portion of the presser bar and the cooperating presser rails connected thereto;

Figure 5 is an enlarged view illustrating the method of mounting the hinged gates; 65

Figure 6 is a horizontal sectional view, taken through the gate supporting frame, showing the gate in plan view;

Figure 7 is a detail view illustrating the drum; 70

Figure 8 is an end view of one of the presser rails; and,

Figure 9 is a view showing the meeting ends thereof.

Referring now to the accompanying drawings by corresponding characters of reference throughout the several views, the numeral 10 designates in general a mine shaft, which is provided with the usual brace beams 11 and across the lower side of which 80 extend the usual ties 12 upon which the track rails 13 are mounted. 75

The gates are shown at 14 and are mounted in a suitable frame including the vertical members 15 and horizontal members 16 85 and 17 the latter of which are provided with recesses 18 near their outer ends, in which the pivotal or hinging members 19 of the said gates 14 are located, thus providing for the proper swinging of the said 90 gates from closed to open position.

Springs shown at 19 serve to normally hold the gates in closed position as shown in Figure 2.

A transversely extending presser bar 20 95 is pivoted as at 21 to one side of the track adjacent one of the rails 13 and has connected to its free end an attaching clip 22 to which a cable 23 is connected.

The cable 23 passes over a pulley 27 attached to a bracket 28 carried by the brace beams 11 and after passing over the pulley is connected to a longitudinally movable rod 28' to which is attached a cable which is wound around the minor portion 29 of the 100 drum 25, which also has a major portion 26 formed thereon. 105

A cable 30 passes over the major portion

of the drum 25 and has attached at one end thereof a weight 31 for a purpose to be later explained. The intermediate portion of this cable operates a pulley 32 and is then attached to one of the gates as shown at 33. A separate cable 34 passes over a pulley 35 and is attached at its opposite ends to the inner ends of the gates as shown in Figure 2.

10 It will thus be obvious that upon the depression of the member 20 the cable 23 will be pulled downwardly, thus moving the rod 28 to the left, as shown in Figure 2 and pulling the gates in opposite directions, to 15 open position.

In order to operate the presser bar 20 suitable channel presser rails, shown at 36, are pivoted at their outer ends at 37 to points adjacent the rails 13.

20 The meeting ends of these members 36 are provided with depending eyes 37 which pass between the rods 38 carried by a frame 39 secured to the upper side of the bar 20.

25 The members 36 work in suitable guides 40 which may be attached to the ties and which will prevent spreading of the said channel presser rails.

As is shown in the drawings the meeting ends of these bars are raised as clearly shown 30 in Figure 9 and the channel members are so arranged adjacent the rails, that the wheels of the car will engage the same and force them downwardly during its passage 35 through the shaft, thus opening the gates which will be automatically closed behind the car by the weight 31, as the car passes through and the wheels leave the rails 36.

It should be further mentioned that the 40 end of the presser bar 20 to which the cable 23 is connected is of such distance from the members 36 that a slight downward movement thereof will give a consequent greater

movement to its free end, thus permitting of the necessary and desired movement of the gates, to open or closed positions.

45 From the foregoing description taken in connection with the accompanying drawings, it will be manifest that a gate operating mechanism for mine shafts is provided, which will fulfil all of the necessary requirements of such a device and it should be understood in this connection that various minor changes in the specific details of construction can be resorted to within the scope of the appended claim, without departing 50 from the spirit or sacrificing any of the advantages of the invention.

Having thus fully described the invention, what I claim as new and desire to protect by Letters Patent is:

60 In a mine shaft having a track located therein gates closing said mine shaft, means for pivotally supporting the gates, a drum having minor and major sections, a transversely extending presser bar, presser rails 65 pivoted at their outer ends to the track, and at their inner ends to the presser bar for depressing the latter upon the passage of a car therover, a cable attached to the presser bar and pivotally connected to the minor 70 portion of the drum, and a cable passes over the major portion of the drum, a weight attached to one end of the cable, and the opposite end of the cable attached to one of said gates and a second cable connecting the 75 gates together whereby upon the opening and closing of one of the gates, the other gate will be opened and closed and a weight attached to one of said cables for returning the gates to closed position.

80 In witness whereof I have hereunto set my hand.

DAVID SYM BAIN.
